UNITED STATES PATENT OFFICE

HENRY W. RICE, OF EAST BOOTHBAY, MAINE

RUDDER AND PROPELLER GEAR DRIVE FOR MOTOR BOATS

Application filed May 28, 1930. Serial No. 456,768.

My invention relates to a combination rudder and propeller gear drive for boats, more particularly to a rudder and propeller gear drive for use on motor boats, and it consists in the constructions, combinations and arrangements herein shown and described.

An object of my invention is to provide a combination rudder and propeller gear drive which accomplishes the steering operation by means of deflection of the propeller as well as the rudder.

A further object of my invention is to provide a device of the type described which provides for efficient operation of the propeller in all the operative positions in which the same is placed during the various steering operations.

A further object of my invention is to provide a combination rudder and propeller gear drive in which those parts which might come into contact with the water are suitably encased or housed to protect the same from said contact.

A still further object of my invention is to provide a device of the type described which is readily adjustable to the needs of individual operators.

A still further object of my invention is to provide a device of the type described which is readily applicable to boats of conventional construction in use today.

A yet further object of my invention is to provide a device of the type described which is simple to manufacture, has few parts, and does not get out of order easily.

Other objects and advantages will appear as the specification proceeds and the invention will be more particularly defined in the appended claim.

My device is illustrated in the accompanying drawings forming a part of this application, in which:

Figure 1 is a sectional view through a boat, showing my device in side elevation set up for operation;

Figure 2 is a sectional view through a boat, showing an end elevation of my device set up for operation;

Figure 3 is an elevational sectional view through my device, with parts thereof shown

in elevation for the sake of clearness of illustration;

Figure 4 is a sectional view, on line 4-4 of Figure 1;

Figure 5 is a further sectional view on line 5-5 of Figure 1.

In carrying out my invention I make use of an ordinary boat 1 having therein an engine (not shown) or other suitable source of power for connection with the drive shaft 60 indicated at 2.

In adapting the boat and associated motor or other power means which is in operative engagement with the shaft 2 to my invention, I cut away in the base or bottom of said boat 65 an aperture 3 which receives therethrough portions of my device.

For securing the elements of my device in position relative to said aperture 3 and consequently the boat 1, as well as for mounting the various parts of the construction, I provide a housing or casing member 4 having thereon a reduced portion 5 for projection through the aperture 3 for tight fixed 70 relation to the base of the boat.

This casing 4 comprises an upper and lower section, generally designated by the numerals 6 and 7, respectively. This upper section or portion may comprise the walls 8 and 9 integrally formed with the lower portion 7, the wall 10 removably secured to the wall 9 and the cover plate 11 which forms the top of the casing. As appears most clearly from an examination of Figure 3, the wall 10 is secured to the wall 9 by means of fasteners 12 80 or any other suitable means while the cover plate 11 is secured to the wall 8 and the wall 10 by means of the screws 13 which may be replaced by any other conventional fasteners.

The wall 8 and the wall 10 are provided 90 with roller bearings 15 or any other suitable form of bearings for the reception therein of a shaft 16 which may be an integral portion of shaft 2 or which may be coupled to said shaft by the coupling means shown at 17. 95 The wall 6 is suitably bossed inwardly, as shown at 18, for mounting this bearing 14 and for receiving the end 19 of the shaft 16, while the wall 10 is apertured, as indicated at 20, for the passage of the shaft 16 therethrough. 100

This wall 10 is further provided with a gland packing, indicated at 21, which prevents entry of foreign material into the casing and adapts the same to the use of a lubricant therein.

5 In the lower or base wall 9 of this upper portion 6 an aperture 22 is provided through which a shaft 23 which I term the intermediate shaft projects. A portion of this wall 10 about the aperture 22 is suitably bossed to mount a bearing 24, which is provided for a purpose that will soon appear.

15 This intermediate shaft 23 is adapted to be driven from the shaft 16 which is actuated by the drive shaft of the motor or other suitable power means by means of miter or bevel gearing interconnecting the same and comprising the bevel gear 25 integrally connecting to the shaft 16 and the bevel gear 26 integrally connected to the shaft 23.

20 The lower portion 7 of the casing 4 is provided with a vertically extending bore 27 which extends through the reduced portion of said part 7 and through a bossed part 28 projecting inwardly from the lower wall of said part 7. It is in this bore that the rotatably mounted propeller and steering means supporting casing 29 is journaled. The cup shaped bearing at the upper extremity of the 25 part 7 in the wall 9 also provides a suitable bearing for journaling the end 31 of this casing member. A sleeve packing 32 positioned for cooperation with the boss member 28 prevents seepage of water from below the boat 30 between the walls of the members 29 and 28 and into the part 7.

35 As will appear most clearly from an examination of Figure 3, this propeller and steering means of the member 28 rotatably mounts therein the intermediate shaft 23 providing at its lower extremity a roller bearing 33 for cooperation with shaft 23 for this purpose.

40 The intermediate shaft 23 projects into a gear chamber 34 at the lower extremity of the member 29 which gear chamber may be of any suitable construction but is shown as consisting of a body formed substantially in the shape of an ovoid. In the tips of this ovoid-shaped member bosses 35 and 36 are provided which are adapted to mount roller-bearings 37 and 38 respectively for rotatably securing in said bosses for projection from one end of said ovoid-shaped member the propeller shaft 39, on which the propeller 40 is secured by the nut 41 or any suitable fasteners.

45 A cap member 42 engages about a projection on the boss 36 to secure the ovoid-shaped member 34 against leakage at this point as well as to permit an operator to have access to the end of the shaft 39 for releasing the same when desired. The opposite end of the ovoid-shaped body is provided with a gland packing 43 which is adapted to prevent seepage of water into the ovoid-shaped body. A cover 50 plate 44 completes the enclosure forming the

ovoid-shaped chamber. It is by these members that seepage of water into the gear chamber 34 and passage of lubricant therefrom into the water is prevented.

55 For steering the boat I equip the casing member 29 with a rudder 45 which as shown most clearly in Figures 3 and 5 may consist of a flat plate of any desired form integrally constructed with the vertically extending portion 29 and integrally connected to the 75 ovoid-shaped member forming the chamber 34 or demountably connected thereto as desired.

60 For performing the steering operation the casing member 29 which is rotatably mounted in the bore 27 and the cup-shaped bearing 30 is provided with a tiller 46 or a steering means of any other desired and suitable construction. In this embodiment I show the tiller consisting of a hand lever 47 having a clamp member 48 at the inner extremity thereof for engagement with a similar clamp member 49 to provide a locking collar secured to said casing 29. The hand lever 47 of this tiller projects through the window or aperture 50 in the portion 7 of the casing 4. The portion 7 may be provided with a window or aperture 51 on the opposite side for permitting positioning of the tiller member for engagement from said side at the will of the operator.

65 From the foregoing description, the use and operation of my device is easily understood. The apparatus is set up as heretofore described with the shaft 2 connected to the 100 drive shaft of the motor or other suitable source of power. This shaft drives shaft 16 which as can be easily understood from an examination of the shafts and gearing of Figure 3, actuates the propeller member 40. 105

70 When the operator desires to steer the boat on a new course, he simply rotates the vertically extending casing member 29 by means of the tiller 47 to change the angle of inclination of the rudder 45 to the boat 1. 110 This movement of the member 29 and associated rudder and gear casing, of course positions the propulsion means at the same angle as is taken by the rudder 45 to aid in the steering operation. It can also be easily understood that because of the gear connection between shafts 39 and 23 the rotation of the propulsion means 40 will not be affected in any way except by a slight variation in the speed of rotation thereof during the 115 turning movement.

75 It is thus easily seen that I have provided a combination propulsion and rudder gear drive for motor boats which enables an operator to variably position said rudder and said propulsion means for steering the boat without material decrease in the efficiency of the operation of said propulsion means.

80 It will also be further seen that I provide a device of the type described which is well 130

adapted to the retaining of a lubricant throughout all of its positions of operation and for preventing the seepage of water into the working parts thereof which are desirable features in constructions of this nature.

It is further seen that the working parts of my device are readily accessible to mechanics or operators who wish to work on the same.

As can be readily understood the tiller permits an easy adjustment to suit the individual needs of an operator.

I claim:

- 15 A propulsion and steering means for boats comprising a stationarily positioned casing having apertures upon opposite sides thereof, a vertically positioned casing rotatably mounted in the stationarily positioned casing, a propulsion means mounted in said vertically positioned casing and adapted for actuation from a suitable source of power, a steering vane positioned on said vertically positioned casing, a tiller mounted on said rotatable casing including a clamp member adapted to partly encircle said rotatable casing, a separate clamp cooperable with said first named clamp member and said casing, whereby said tiller may be detached and 30 projected through a desired aperture in said stationary casing.

HENRY W. RICE.
